CLAIM

We claim the ornamental design for a basketball, as shown and described.

DESCRIPTION

FIG. 1 is a front view of a basketball of the present design; FIG. 2 is a side view of the basketball of FIG. 1; FIG. 3 is the opposing side view of FIG. 2; and, FIG. 4 is a rear view of the basketball of FIG. 1. The ornamental design that is claimed is shown in solid lines in the drawings. The broken (dashed) lines shown in FIGS. 1 through 4 are included only for the purpose of illustrating environmental elements, and form no part of the claimed design.

1 Claim, 4 Drawing Sheets
